UNITED STATES PATENT OFFICE.

THEODORE G. SPRINGER, OF NEW YORK, N. Y.

PROCESS OF AND APPARATUS FOR MANUFACTURING GAS.

SPECIFICATION forming part of Letters Patent No. 361,190, dated April 12, 1887.

Application filed October 28, 1886. Serial No. 217,469. (No model.)

To all whom it may concern:

Be it known that I, THEODORE G. SPRINGER, a citizen of the United States, residing at New York city, in the county of New York and State 5 of New York, have invented certain new and useful Improvements in Process of and Apparatus for Manufacturing Gas; and I do hereby declare the following to be a full, clear, and exact description of the invention, such as will 10 enable others skilled in the art to which it app pertains to make and use the same.

This invention relates to the process of and apparatus for manufacturing gas, more particularly adapted for motive power and heating 15 purposes.

The object of the invention is to greatly cheapen the manufacture of superior heating-gas, by first producing a low-grade gas by means of cheap material, such as cheap fuel, 20 for heating up one or more decomposing-cham bers containing refractory material, and then using cheap hydrocarbons, like petroleum or heavy oils or tar, for decomposition, together with steam in excess, in contact with said 25 heated refractory material, producing carbonic acid and hydrogen, and then converting such resulting low-grade gases into marsh-gas and carbonic oxide by passing them through a converting body of incandescent hard carbon.

Another object is to provide for economically utilizing the gaseous products from cheap low-grade fuel and also the waste gaseous products from the high-grade hard carbon for heating a large body of refractory material (in one or 30 more compartments) to serve for superheating steam and decomposing it, together with cheap hydrocarbons, whereby a large volume of low-grade gas is made at small expense, and then to convert such gas into high-grade heating- 35 gas, composed of marsh-gas and carbonic oxide, by passing it through a body of incandescent high-grade hard carbon, whereby but a small per cent. of expensive fuel is used, while a superior quality of heating-gas is produced.

In carrying out my invention a low-grade fuel, such as cheap bituminous coal or any kind of slack coal or wood, is used in a Siemens or other gas-producer for making cheap fuel-gas, which is burned while hot by means of a 40 suitable air-supply in a large chamber containing refractory brick-work, which I call my 45 "superheating and decomposing chamber;"

and at the same time I heat a comparatively small body of high-grade hard carbon, such as anthracite coal or hard coke, to incandescence 55 in a second fuel-chamber, by means of an air-blast, and burn the resulting gaseous products in the said brick-work superheating and decomposing chamber, and store the heat in the refractory brick. This second fuel-chamber, 60 containing the body of incandescent hard carbon, constitutes my gas-converting chamber or furnace.

The brick-work superheating and decomposing chamber and the body of hard carbon 65 in the gas-converting furnace having been heated to the desired temperature, the air-blasts are shut off and steam is superheated and then decomposed in conjunction with a limited supply of cheap hydrocarbon oil in 70 contact with the hot brick-work, so as to form a large volume of carbonic acid and hydrogen, and such gases are then passed through the incandescent hard carbon and thereby converted into carbonic oxide and light carbureted hydrogen, which is passed off for storage 75 or immediate use.

The matter constituting my invention is defined in the claims.

In the accompanying drawings, Figure 1 represents a vertical longitudinal section of the apparatus. Fig. 2 represents a horizontal section thereof, showing two sets of superheating and decomposing chambers and two converting chambers or furnaces in one structure. 80 85

The apparatus is composed of three principal parts, viz: the furnace A, of any suitable construction for generating cheap producer-gas, the superheater and decomposer G, containing refractory brick, and the gas-converting chamber or furnace B, for incandescent hard carbon. These chambers may be built in one structure separated by partition-walls, as shown, and the structure may contain two sets of superheaters, G, two converting furnaces, B, and one large producer-furnace, A, 90 as shown in Fig. 2. If preferred, however, the chambers may be built in separate structures, each inclosed in a tight iron jacket, in the well-known manner. The chambers are 95 built of fire-brick, and when united in one structure are surrounded by one tight iron shell or jacket.

The producer-furnace A may be built large

enough to supply two sets of superheating and decomposing chambers, as shown in Fig. 2, and is provided at the top with fuel-passage *a*, having cap *x*, and with the gas-flue *b* *b'* and valve-box *u*, having valve-seat *t*. A conical valve, *c*, having an operating stem and lever, is arranged in box *u* to close flue *b*. The partition-wall *O* separates furnace *A* from superheater and decomposer *H*, and up through such wall is passed the air-blast pipe *m*, having a bent nozzle, *m'*, arranged in flue *b*, and opening toward chamber *H*, for drawing off the producer-gas and forcing it into chamber *H*, and there causing its combustion. The air is heated by passage through pipe *m* in the wall *O*.

The steam superheater and decomposer *G* is divided by partition *R* into vertical chambers *H* and *H'*, and chamber *H* is divided into upper and lower compartments by perforated brick arches *k* *k'*, which also serve to support the brick checker-work with which the chamber is filled. Chamber *H'* has at its bottom a perforated arch, *l*, for supporting its brick-work. Chambers *H* and *H'* are connected at the base below arches *k* *l* by passage *r* in wall *R*. Air-blast pipes *L* and *L'* connect with chamber *H* at the top and below arch *k'*, as shown. Supply-pipes *e* *e'* for hydrocarbon oil connect with the base of chamber *H* and below its arch *k'*. Chamber *H* has at the top a passage, *h*, and tight lid or cap *x'*. A steam-supply pipe, *s*, connects with the top of chamber *H'*, and such chamber is provided at its top with passage *h'*, having lid or cap *x''*. The converting-furnace *B* is separated from chamber *H* by partition-wall *T*, and is provided at the base with the usual grate, *c'*, ash-pit *w*, and door *d*. At the top it is provided with fuel-opening *h''*, having lid *x'''*. A gas-flue, *N*, connects the top of chamber *H* with the top of furnace *B*. An air-blast pipe, *D*, and gas take-off pipe *C* connect with ash-pit *w* of furnace *B*. In practice the air-blast pipes will connect with a blower or pump, and gas take-off pipe *C* will connect with a seal and wash-box. (Not here shown.) A partition-wall, *P*, separates the two sets of superheating and decomposing chambers *H* *H'* and the two furnaces *B*, as shown in Fig. 2.

The operation is as follows: A fire is made in producer *A*, and it is supplied with cheap low-grade fuel to produce a cheap producer-gas for heating up the refractory brick-work in chambers *H* and *H'*. When the gas flows off freely from the producer, valve *c* and lid *x'* are opened and the hot gas is burned by a supply of air from nozzle *m'* in chamber *H*. The products pass down and are given a second supply of air by pipe *L'* below arch *k'*, for producing complete combustion, and the hot products pass through chamber *H*, through passage *r*, and then up through chamber *H'*, and out through passage *h'*, at a low temperature, having imparted their heat to the brick-work. At the commencement of the operation a fire is also kindled in furnace *B*, and it is gradu-

ally fed with high-grade hard coal during the admission of the air-blast by pipe *D* till a deep body of incandescent fuel is formed. The gaseous products, passing off from the fuel in chamber *B*, flow through flue *N* into the top of chamber *H*, where they are burned by blasts of air admitted through pipes *L* *L'*, and aid in highly heating the refractory brick-work in chambers *H* *H'*. The brick-work in these chambers is to be heated to a very high degree, as the chambers are to be used for superheating steam and decomposing it in conjunction with a regulated and limited supply of oil. The high-grade hard carbon in chamber *B* having been heated to incandescence, and the chambers of refractory brick-work having been heated to the desired high temperature, the air-blasts are shut off, valve *c* is closed, and the lids *x*, *x'*, *x''*, and *x'''* are tightly closed; then steam is admitted by pipe *s* into the top of chamber *H'* and superheated by passage downward through the heated brick-work. It flows through passage *r* into chamber *H*, where there is admitted a limited and regulated supply of hydrocarbon oil by pipe *e* or *e'*, or both, as desired, the oil being in suitable proportion to form, by decomposition with the steam, carbonic acid and hydrogen. This mixture of gases is passed through flue *N* and down into contact with the incandescent hard carbon, where the carbonic acid is fully converted into pure carbonic oxide and the hydrogen is partially carbureted. The completed gas, after passage through the fuel in chamber *B*, is finally conducted off by pipe *C* to the seal and wash box.

It has heretofore been proposed to decompose steam in a retort and pass the resulting gas, together with oil, through a retort containing anthracite coal for making illuminating-gas. It has also been proposed to make illuminating-gas by passing steam and oil directly into a retort containing heated carbon; but these processes differ from my invention, the distinguishing features of which are stated below.

It will be understood that the particular object of using the producer-furnace *A* is that thereby a cheap low-grade fuel may be advantageously utilized for highly heating a large body or bodies of refractory brick-work, in which oil with steam in excess are decomposed into hydrogen and carbonic acid, while such low-grade fuel would not answer, on account of its impurities and other defects, for decomposing steam or for converting the above-mentioned carbonic acid and hydrogen into high-grade heating-gas, as such fuel would foul the gas with sulphur and other impurities.

It will also be understood that the particular object of chamber *B*, with its body of high-grade hard carbon, is to convert the hot low-grade gases resulting from the decomposition of steam and oil into pure high-grade water-gas with a comparatively small consumption of the more expensive high-grade fuel. It will be seen that since the steam is decom-

posed in conjunction with cheap hydrocarbon oil in the large body of brick-work, which has been mostly heated by producer-gas, and that the gases resulting from the decomposed steam and oil are passed in a highly-heated state into contact with the hard carbon in chamber B, such expensive fuel is consumed very slowly, and thus a large saving in the fuel account is effected.

10 Having described my invention, what I claim, and desire to secure by Letters Patent, is—

15 1. The process of manufacturing gas, which consists in blasting a body of fuel with air and heating it to incandescence, burning the resulting gaseous products and storing the heat in a body of refractory material, then decomposing hydrocarbon with steam in excess by passing them in contact with such heated refractory material into hydrogen and carbonic acid, then passing such gases through the body of incandescent fuel, and thereby converting them into marsh-gas and carbonic oxide.

20 2. The process of manufacturing gas, which consists in highly heating a body of refractory material by the combustion of producer-gas, and also heating to incandescence a body of hard carbon, then forming a mixture of hydrogen and carbonic acid by first superheating steam in contact with part of the refractory material, and then adding hydrocarbon oil in suitable proportion to decompose the steam into carbonic acid and hydrogen, and then converting the resulting gases into marsh-gas and 35 carbonic oxide by passing them through the body of incandescent hard carbon.

30 3. The process of manufacturing gas, which consists in first making a cheap heating-gas in a producer from cheap fuel and discharging the gases into a chamber containing re-

fractory material, and at the same time blasting a body of carbonaceous material to a high heat in a separate chamber, discharging the products of such combustion into the chamber containing the refractory material, then 45 burning the producer-gas and the products of combustion and storing the heat in the refractory chamber, then decomposing steam and hydrocarbons in contact with the highly-heated refractory material into carbonic-acid 50 and hydrogen gases, and then passing said gases through the heated carbonaceous material to convert the carbonic-acid gas into carbonic oxide and the hydrogen into light carbureted hydrogen.

55 4. In apparatus for manufacturing gas, the combination, with a gas-producer and a chamber containing refractory material for decomposing hydrocarbon oil and steam and having supply-pipes therefor, of a gas-converting furnace and suitable connection, as described.

60 5. In apparatus for manufacturing gas, the combination of a producer, a chamber containing refractory material and having a steam superheating compartment, and steam and oil supply pipes, and a gas-converting furnace.

65 6. In apparatus for manufacturing gas, a decomposing-chamber containing refractory material provided with a steam superheating compartment having a steam-supply pipe at 70 the top and a decomposing-compartment having an oil-supply pipe, in combination with a producer and a converting-furnace, both connecting with its top, for the purpose set forth.

75 In testimony whereof I affix my signature in presence of two witnesses.
